UNITED STATES PATENT OFFICE.

HARVEY HUBBELL, OF BRIDGEPORT, CONNECTICUT.

CLUSTER-SWITCH.

SPECIFICATION forming part of Letters Patent No. 734,876, dated July 28, 1903.

Application filed November 21, 1902. Serial No. 132,234. (No model.)

To all whom it may concern:

Be it known that I, HARVEY HUBBELL, a citizen of the United States, residing at Bridgeport, county of Fairfield, State of Connecticut, have invented a new and useful Cluster-Switch, of which the following is a specification.

My invention has for its object to provide an electric switch which shall be especially adapted for use where it is desired to close a plurality of incandescent-lamp circuits, thereby lighting lamps or groups of lamps successively and to open the circuits for the purpose of extinguishing the lamps thereon either successively or simultaneously.

With this and other ends in view I have devised the novel cluster-switch of which the following description, in connection with the accompanying drawings, is a specification, reference characters being used to indicate the several parts.

Figure 1 is a vertical section of a cluster center, showing my novel switch in elevation; Fig. 2, a section of the frame on the line 2 2 in Fig. 1, showing the mechanism of the switch in edge view; Fig. 3, an elevation of the frame and insulating-body detached; Fig. 4, a double view showing the supporting-rod in section and corresponding face views of the contact-wheel and the inclines and contact-plates on the insulating-body. Figs. 5, 6, and 7 are diagrammatic face views of contact-wheels and the corresponding inclines and contact-plates, illustrating variant forms in which the principle of the invention may be carried into effect; and Figs. 8 and 9 are diagrammatic views illustrating other modified forms of my novel switch, the supporting-rod being in section and the contact-plates and current-plate on the contact-wheel being in elevation in each view.

Certain of the mechanical features of the switch itself do not differ materially from the switches illustrated and claimed in my former Letters Patent No. 565,541, dated August 11, 1896, No. 649,308, dated May 8, 1900, and No. 693,799, dated February 18, 1902.

The essential features of my present invention are an insulating-body carrying a plurality of contact-plates leading to inde-

pendent circuits or groups of circuits and a rotatable contact-wheel having spring-arms adapted to engage the contact-plates.

10 denotes the frame of the switch to which the shell 11 of a cluster center is attached and which is itself attached to a stem 12.

13 is a brace carried by the stem and acting to support the shell, as fully illustrated and described in my pending application, Serial No. 128,851, filed October 27, 1902.

14 denotes the caps of incandescent-lamp sockets, which are shown as secured to the shell in the manner set forth and described in my said pending application referred to.

A denotes an insulating-body which is shown as rigidly secured to the frame, and B a supporting-rod which is rigidly secured to the body and projects therefrom on the inner side, as clearly shown in Fig. 2. This supporting-rod receives the electrical current, which passes to the contact-wheel and thence to the contact-plates, as I shall proceed to describe.

C denotes an operating-wheel, and D the contact-wheel, both of which are mounted to turn on the supporting-rod. The operating-wheel is preferably made of insulating material, as porcelain or vulcanized fiber. If not made of insulating material, it must of course be perfectly insulated. The operating-wheel is provided on its inner face with a lug or lugs 15, adapted to engage recesses 16 in the contiguous face of the contact-wheel. The number of recesses in the face of the contact-wheel will of course be varied to suit the requirements of special switches. In practice the contact-wheel may be made of metal or of insulating material, as porcelain or vulcanized fiber, as preferred. When made of insulating material, the contact-wheel has rigidly secured thereto a current-plate 17, which receives the current from the supporting-rod and which in turn has secured thereto outwardly-projecting spring-arms 18.

19 in Figs. 4 and 6 denotes outwardly-projecting dummy spring-arms carried by the contact-wheel, but not attached to current-plate 17, and consequently not receiving any current. These dummy spring-arms are provided merely for the purpose of balancing the

current-wheel and insuring that it work evenly and may or may not be used, as preferred.

The insulating-body A, which is shown as attached to the frame, is provided on its inner face with a plurality of inclines 20, arranged in the form of a circle or a plurality of concentric circles, which may be made of the material of the plate, and are adapted to 10 be engaged by the spring-arms upon the contact-wheel. Part but not all of these inclines are provided with contact-plates 21, which are connected by means of screws 22 with blocks 23 on the outer face of the body. Each block 15 is provided with one or more binding-screws 24 for the attachment of circuit-wires 25, it being of course obvious that each circuit may contain one or a plurality of lamps.

The mechanical operation of my present 20 switch is substantially the same as the mechanical operation illustrated and described in my said former patents referred to.

25 26 denotes a spring for the operating-wheel, one end of which is shown as secured to supporting-rod B and the other to the operating-wheel, as at 27. The switch is shown as operated by a chain 28, one end of which is detachably secured to a catch 29 on the operating-wheel, the chain extending upward and 30 partly around the operating-wheel and downward through the bottom of the frame and shell at the center, as clearly shown in Fig. 1. I preferably, as shown in the drawings, secure the frame and shell together by means 35 of a threaded hub 32, passing through both frame and shell at the center of the bottom and having an external ornamental head, between which and the frame the shell is clamped, and a hole 33, through which the 40 chain passes.

30 30 denotes an arm extending outward from the periphery of the operating-wheel and adapted to engage stops 31 on the frame to limit the oscillation of the operating-wheel in 45 each direction. Spring 26 acts to return the operating-wheel to its normal position after each actuation and also to retain the operating-wheel and the contact-wheel in operative position—that is, with the spring-arms in reliable engagement with the inclines and contact-plates on the insulating-body, as clearly shown in Fig. 2.

It will be readily understood that when the 50 chain is pulled the operating-wheel will be oscillated until its movement is stopped by engagement of arm 30 with one of the stops, and through the engagement of lugs 15 with recesses 16 in the contact-wheel the latter will be carried forward with it and the spring- 55 arms will pass over inclines upon the insulating-body and off from the inclines upon which they were resting at the commencement of the movement and upon the next succeeding inclines. As soon as the pull upon the chain 60 is relieved spring 26 will return the operating-wheel to its normal position—that is, un-

til the backward movement is stopped by the engagement of arm 30 with the other stop. Turning now to diagrammatic Fig. 5 in connection with Figs. 1, 2, 3, and 4, I will explain more specifically the form of the invention illustrated in these figures. This form provides for two independent circuits or groups of circuits, as a plurality of circuits may be operated from each contact-plate. 70 Supposing the circuits to be open, the first pull upon the chain will close the first circuit, or rather all circuits operated from the first contact-plate, the second pull closes the second circuit or group of circuits, the third 80 pull opens the first circuit or group of circuits, leaving the second circuit or group of circuits closed, and the fourth pull opens the second circuit or group of circuits. A fifth pull would start the operation over again by 85 closing the first circuit or group of circuits again. The special construction required to produce the above results will be obvious from the first five figures of the drawings. It will be noted that the contact-wheel is provided with two spring-arms 18, which in Fig. 4 are shown as balanced by two dummy spring-arms 19—that is, spring-arms that are not adapted to be brought into the circuit—and the insulating-body is provided with four 90 inclines 20, two of which are provided with contact-plates 21, which are adapted to be placed in the circuit. Suppose now that the two spring-arms 18 upon contact-wheel D are in engagement with the inclines upon insulating-body A, that are not provided with contact-plates 21. It is obvious that both circuits or groups of circuits will be open. A single pull upon the chain will place one 95 of the spring-arms 18, which for convenience I will call the "first" spring-arm, in engagement with the first contact-plate on the insulating-body, and will thus close the first circuit or group of circuits. The next pull upon the chain will place the first spring-arm 100 18 in engagement with the second contact-plate and the second spring-arm 18 in engagement with the first contact-plate, thus closing both circuits or groups of circuits. The next pull upon the chain will throw the 105 first spring-arm 18 off from the second contact-plate and will throw the second spring-arm 18 upon the second contact-plate, thus opening the first circuit or group of circuits, but leaving the second circuit or group of 110 circuits closed. A fourth pull upon the chain throws the second spring-arm off from the second contact-plate, and thus opens the second circuit or group of circuits. A fifth pull upon the chain would place the first spring-arm 115 in engagement with the first contact-plate, and thus again close the first circuit or group of circuits.

In diagrammatic Fig. 6 I have illustrated a form of the invention in which there are 120 three independent circuits or groups of circuits, and six actuations of the operating-

wheel are required to complete the operation of the switch. The insulating-body is provided with six inclines, three of which are provided with contact-plates 21, and the contact-wheel is provided with three spring-arms 18. Starting with the circuits all open, the first actuation closes the first circuit or group of circuits, the second actuation closes the second circuit, leaving the first closed, the third closes the third circuit, leaving the first and second closed, the fourth opens the first circuit, leaving the second and third closed, the fifth opens the second circuit, leaving the first open and the third closed, and the sixth opens the third circuit, leaving the first and second also open.

In diagrammatic Fig. 7 I have illustrated a form of the invention in which there are three independent circuits or groups of circuits, only two of which, however, can be closed at a time, the complete operation of the switch being effected by three actuations of the operating-wheel. The insulating-body is provided with six inclines, three of which are provided with contact-plates 21, as in Fig. 6, but differently arranged. In the present form a single incline provided with a contact-plate 21 is followed by a single insulating-incline, which in turn is followed by two inclines provided with contact-plates, which in turn are followed by two insulating-inclines. The current-plate 17 upon contact-wheel D in this form is provided with two spring-arms 18, which are placed diametrically opposite to each other. Starting with the circuits open—that is, with both spring-arms 18 in engagement with insulating-inclines (i. e., inclines not provided with contact-plates)—the first actuation will move one of the spring-arms upon a contact-plate and will close a circuit, the other spring-arm remaining on an insulating-incline. The second actuation will move the spring-arm that was previously on an insulating-incline upon a contact-plate and will move the opposite spring-arm which was previously on a contact-plate upon the contiguous contact-plate, thus leaving the two spring-arms in engagement with diametrically opposite contact-plates and leaving two circuits closed. The third actuation will place the spring-arms upon the contact-wheel in the starting position—that is, in engagement with two diametrically opposite insulating-inclines, leaving the three circuits open. A fourth actuation will close a single circuit as before, a fifth actuation will close two circuits as before, and a sixth actuation, completing the revolution of the contact-wheel, will open all the circuits again.

In diagrammatic Figs. 8 and 9 I have illustrated forms of the invention which are simply applications of the form illustrated in diagrammatic Fig. 7 to a greater number of circuits, the desired result being attained by the use of a greater number of inclines arranged in the form of concentric circles. In the form illustrated in Fig. 8 there are two

concentric circles of inclines, each circle having eight inclines, and the current-plate 17 upon contact-wheel D is provided with four spring-arms 18, arranged in diametrically opposite groups of two, so that there will be two spring-arms, one in each group, constantly in engagement with each circle of inclines. The operation, which I will describe more fully in connection with Fig. 9, is briefly as follows: Starting with all circuits open, the first actuation of the operating-wheel will close one circuit, the second will close two circuits, the third will close three circuits, and the fourth will open all circuits again, and so on. In the form illustrated in Fig. 9 there are three concentric circles of inclines, each circle having ten inclines, and the current-plate 17 upon contact-wheel D is provided with six spring-arms 18, arranged in diametrically opposite groups of three, so that there will be two spring-arms, one in each group, constantly in engagement with each circle of inclines. In this form, starting with all circuits open, the first actuation of the operating-wheel will close one circuit, the second will close two circuits, the third will close three circuits, the fourth will close four circuits, and the fifth will open all circuits again, and so on. The arrangement of the contact-plates upon the inclines is as follows: Describing the inclines in radial groups of three, beginning at the top and going around toward the left, the first group comprises three insulating-inclines. In the second group the incline in the outer circle is provided with a contact-plate 21 and the inclines of the two inner circles are insulating-inclines. The third group is like the second. In the fourth group the two outer inclines are provided with contact-plates, the inner incline being an insulating-incline. In the fifth group all the inclines are provided with contact-plates. In the sixth and seventh groups all the inclines are insulating-inclines, and in the eighth, ninth, and tenth groups the outer incline in each group is provided with a contact-plate, the two inner inclines being insulating-inclines.

The operation is as follows: In the position shown in Fig. 9 the opposite groups of spring-arms 18 are in engagement with opposite groups of insulating-inclines, so that all the circuits are open. The first actuation of the operating-wheel will place one of the outer spring-arms in engagement with a contact-plate 21, thus closing one circuit, all of the other spring-arms being in engagement with insulating-inclines. The second actuation will place the outer spring-arm in each group in engagement with a contact-plate, the inner and intermediate spring-arms in each group being in engagement with insulating-inclines, so that two circuits will be closed. The third actuation will place the outer and intermediate spring-arms in one group and the outer spring-arm in the other group in engagement with contact-plates, the inner

spring-arm in one group and the inner and intermediate spring-arms in the other group being in engagement with insulating-inclines, so that three circuits will be closed. The 5 fourth actuation will place the three spring-arms in one group and the outer spring-arm in the other group in engagement with contact-plates, the inner and intermediate spring-arms in the latter group being in engagement 10 with insulating-inclines, so that four circuits will be closed. The fifth actuation, which completes a half-rotation of the contact-wheel, and completes the operation of the switch, places all the spring-arms in both groups in 15 engagement with insulating-inclines, thus opening all circuits.

Having thus described my invention, I claim—

1. The combination with an electric switch, 20 a frame by which it is carried, an operating-chain and a cluster-center shell inclosing the frame, of a threaded hub passing through the shell and the frame at the center of the bottom and having a hole through which the chain 25 passes.

2. The combination with an electric switch, a frame by which it is carried, an operating-chain and a cluster-center shell inclosing the frame, of a threaded hub having a head upon which the bottom of the shell rests and between which and the frame the shell is clamped and a vertical hole through which the 30 chain passes.

3. A cluster-switch comprising a frame, an insulating-body having a plurality of inclines, 35 contact-plates on part but not all of said inclines, each contact-plate forming part of an independent circuit, a rotatable contact-wheel having spring-arms adapted to engage contact-plates to close circuits and an outwardly-extending arm and stops upon the frame 40 which are engaged by said arm to limit the oscillation of the operating-wheel.

In testimony whereof I affix my signature in presence of two witnesses.

HARVEY HUBBELL.
